UNITED STATES PATENT OFFICE

2,006,927

AIR CLEANER

Wilfred W. Lowther, Minneapolis, Minn., assignor to Donaldson Company, Inc., St. Paul, Minn., a corporation of Minnesota

Application December 17, 1934, Serial No. 757,828

2 Claims. (Cl. 183—15)

My present invention relates to air cleaners and is in the nature of an improvement on or modification of the air cleaners disclosed and claimed in my pending applications, S. N. 702,482, and 702,483, filed of date December 15, 1933 which have now matured into Patents No. 2,000,706, granted May 7, 1935, and No. 1,991,758, granted Feb. 19, 1935, respectively. This invention relates particularly to an improved relative arrangement of 10 casing, air intake and outlet conduits and intermediate air passages, whereby the flow of air through the filtering chamber is equalized and made substantially even throughout the cross-sectional area thereof.

Generally stated, the invention consists of the novel devices, combinations of devices and arrangement of parts hereinafter described and defined in the claims.

In the accompanying drawing, which illustrates 20 the invention, like characters indicate like parts throughout the several views.

Referring to the drawing:

Fig. 1 is a view partly in side elevation and partly in vertical axial section, showing an air cleaner involving my invention; and

Fig. 2 is a horizontal section taken on the line 2—2 of Fig. 1.

The air cleaner shown involves an outer casing or shell that is preferably in the form of an upright cylinder 3, the lower end of which is primarily open. An axial air intake tube 4 extends downward through the casing 3. A large or main oil well 5 of cup-shaped form is telescoped onto the lower end of the casing 3 and closes the lower 35 end of the latter.

To securely but detachably hold the well telescoped onto the casing, as stated, nut-equipped bolts 6 are passed through lugs 7 and through the ends of a bar 8 that is applied to the bottom of the oil well. At the upper end of the casing is an air outlet chamber 9 that is formed between annular baffle plates 10 and 11. The upper baffle plate 10 is secured to the upper end of the air inlet tube 4 and to the upper end of the casing. The lower baffle plate 11 is secured to the air tube 4 and to the casing 3 at a point considerably below a lateral air outlet passage 12, which latter is adapted and intended to be connected to the carburetor of an internal combustion 50 engine. As an important feature, the lower baffle 11 which constitutes the bottom of the air outlet chamber 9 is formed with an eccentric annular air passage 13, the narrowest portion of which is nearest to the lateral outlet passage 12 and the 55 widest portion of which is at a point diametrical-

ly opposite to said outlet passage. Also it will be noted by reference particularly to Fig. 2 that the outer portion or rim of the baffle 11 is widest adjacent to the outlet port 12 and is narrowest at a point diametrically opposite to said outlet passage. Otherwise stated, the eccentric air passage 13 progressively increases, and the outer rim of the baffle 11 progressively decreases in width in both directions circumferentially from said outlet port 12. The importance of this structure 10 will be later considered. Within and secured to the bottom of the oil well 5 is an oil cup 14 that is of much less diameter than the oil well, of considerably greater diameter than the lower end of the intake tube 4 and the upper end of which is considerably above the plane of the lower edge of the air tube.

Within the casing surrounding the air intake tube is an annular screen preferably made up of woven wire screen elements. These screen elements 15 may take various forms, but as shown, are of a type and arrangement disclosed and claimed in the application of Frank A. Donaldson entitled "Air cleaner", filed of even date herewith.

An expanded air intake chamber 16 is formed 25 at the upper end of the air intake tube 4 by the annular baffle 10 and by an upper baffle plate 17 which, at its edge is secured to the top of the casing. This baffle 17 is provided with circumferentially spaced air intake ports 18 which constitute no part of my present invention, but are 30 preferably of the arrangement disclosed and claimed in the pending application of Frank A. Donaldson, S. N. 722,458, filed of date April 26, 1934 which has now matured into Patent No. 35 1,992,025, granted Feb. 19, 1935.

Operation

The oil well and cup will be primarily filled approximately to the level of the top of the cup 40 20, but when the engine is in action, partial vacuum will be produced in the air chamber 9 and this, of course, will draw air downward through the air intake tube 4 and through the oil in the cup. By the inrush of air, the 45 oil will be displaced and carried upward through the annular space between the lower end of the air tube and the rim of the cup, and from thence will be carried upward through the screen elements. The extent to which the air will carry 50 the oil upward through the screen elements will, of course, depend largely upon the speed of the engine and the velocity of the air. Before the oil reaches the uppermost screen element, however, it will be released from the air current 55

and will flow back over and through the screens. In running down onto and through the screens, the oil will form films over the openings in the screen through which the air must pass so that all the dust carried by the air will be taken from the air and returned with the oil downward and back to the oil well.

Inasmuch as the lateral air outlet passage 12 is eccentric to the axis of the air outlet chamber 8, the highest vacuum will be produced on that side immediately adjacent to the said outlet. With an eccentric air passage in the baffle forming the bottom of the air chamber 8, there will be a tendency for the air to drift to that side on which the outlet is located and this would produce an uneven flow of oil and air upward through the screens. This tendency of the air draft to drift as stated is overcome and neutralized by the above described eccentric arrangement of the air passage in said bottom-forming baffle, and as has been demonstrated in practice, an even flow of air and oil through the screen at all circumferential points thereof can be accomplished. In practice, this novel arrangement of the intermediate air passage, to wit: the passage in the baffle 11 in respect to the lateral or eccentrically located air outlet has been found to increase the air capacity and cleaning efficiency of the air cleaner and hence to be of very great importance. From what has been said, it will be understood that the air cleaner illustrated in the drawing is capable of modifications within the scope of my invention as herein disclosed and claimed.

In the preferred arrangement of the invention above described, the dust and oil intercepting means located between the air inlet and air out-

let is in the form of wire screens, but the said dust-intercepting means may, of course, take various forms so far as the present invention is concerned. By offsetting the passage in the baffle which is located between the dust and oil-intercepting means and the air outlet in a direction opposite to the direction in which the air outlet is offset from the axis of the casing, the even flow of air through the screens and of oil through certain of the screens, is insured.

5

10

What I claim is:

1. In an air cleaner, the combination with a casing having an oil well at its bottom and an axial air inlet tube leading to said oil well, of a screen within said casing surrounding said air intake tube above said oil well, said casing, at a point above the screen being formed with an annular air outlet chamber with an air outlet passage at one side thereof, the bottom of said air outlet chamber being formed by an annular baffle located above said screen and provided with an eccentric annular air passage, the radial dimension of which is narrowest immediately adjacent said outlet passage and is widest at the diametrical opposite point, the intake end of said air intake tube being extended upward through said air outlet chamber.

2. In an air cleaner, a casing having an air inlet and an air outlet that is offset from the axis of the casing and between said inlet and outlet an intermediate dust-intercepting means, and a baffle between the latter and said air outlet, said baffle forming an air passage that is eccentrically offset from the axis of the casing in a direction opposite from the direction of offset of said air outlet.

WILFRED W. LOWTHER.
